UNITED STATES PATENT OFFICE.

RALPH R. TURNER AND RALPH R. TURNER, JR., OF CHARLOTTE, NORTH CAROLINA.

ELECTRIC FAN.

Application filed March 29, 1927. Serial No. 179,299.

This invention relates to electric fans and more particularly to the construction of a rotating electric fan.

An important object of the invention is to provide a supporting base structure for use with fans, which may be applied to the ordinary oscillating fan structure to convert the same to a rotating structure.

A further object of the invention is to provide a device of this character which will permit the fan to be used in either normal or inverted position.

A still further object of the invention is to provide a novel and improved structure of this character facilitating the transmission of current to the motor by which the fan is operated.

These and other objects we attain by the construction shown in the accompanying drawings, wherein for the purpose of illustration is shown a preferred embodiment of our invention and wherein:

Figure 1 is a side elevation partially in section of an electric fan constructed in accordance with our invention;

Figure 2 is a section on the line 2—2 of Figure 1;

Figure 3 is a transverse sectional view therethrough;

Figure 4 is a side elevation of the gear guard;

Figure 5 is a section on the line 5—5 of Figure 4;

Figure 6 is a section on the line 6—6 of Figure 1.

Referring now more particularly to the drawings, the numeral 10 generally designates the motor casing of a fan and 11 the armature shaft of the motor. In the present illustration, the motor casing is illustrated as that of the ordinary oscillating fan structure, which includes a housing 12 depending from one end bearing 13 of the armature shaft and within which is rotatably mounted a shaft 14 driven from the armature shaft 11, as at 15.

In accordance with our invention, we provide a base 16 having an upstanding neck, generally designated at 17. This neck is formed in two sections 18 and 19, of which the section 18 has means, whereby it may be secured to the motor casing and the section 19 is secured directly to the base 16. Arranged in the neck structure and extending into the base is an assembly comprising an inner conducting tube 20, an inner insulating

ring 21 surrounding the conducting tube, an outer conducting tube 22 surrounded in turn by an outer insulating tube 23 and an outer casing tube 24, which is preferably 60 constructed of steel. The tubes 20 to 24 progressively decrease in length and are so arranged at opposite ends thereof, the ends of all of the tubes are exposed. The outer casing tube 24 rotatably fits the interior of the 65 neck section 19 and is secured in position in the neck section 18 by screws 25.

Surrounding this outer tube, intermediate the ends thereof, is a collar 26 forming a carrier for bearing balls 27, which interpose between adjacent ends of the neck sections 18 and 19. The lower end of the casing tube is exteriorly threaded and has mounted thereon a threaded ring 27' and a lock nut 28 therefor. The ring 27' opposes the lower 75 end of the lower neck section 19 and surrounding the casing tube between the ring and the lower end of the neck section is a collar 29 similar to the collar 26.

The upper end of the casing section 19 has 80 secured thereto by screws 30 a baffle gear 31, the securing elements of which are covered by a plate 32 forming a seat upon which the balls 27 engage. Secured to the upper section is a supporting arm 33, the lower end 85 of which provides a bearing 34 for a shaft 35 having at its opposite ends pinions 36 and 37 for engagement with the gear 31 and a gear 38 carried by the lower end of the shaft 35 respectively. It will be obvious that as the 90 armature shaft 11 rotates, this rotation will be transmitted to the gear 38 and the gear 36 thereby caused to rotate, with the result that the housing and upper neck section will rotate with relation to the base. It will also 95 be obvious that whether the fan be arranged in the ordinary position or inverted, it will be supported from ball bearings, so that the resistance afforded to rotation will be materially reduced.

Arranged within the base 16 is an insulating strip 39 supported from the wall of the base and having at its inner end resilient contact strips 40 and 41 engaging the exposed lower ends of the tubes 22 and 20 respectively. Certain of the securing elements 42 of these strips provide binding screws, whereby the feed wires 43 may be attached thereto. At the upper end of the neck section 18, the tubes 20 and 22 are electrically connected to 110 the motor leads 44.

A protecting housing is provided to cover

the gearing comprising a casing formed in two sections 45, each of which is notched at its upper and lower walls, as at 46, so that when the sections are combined, openings 5 are provided, for the reception of the neck sections 18 and 19. In the formation of the notches in the upper wall, tabs are left at 47, which may be bent upwardly and engaged with the binding screws 25, holding the tube 10 24 in position. Adjacent edges of the upper wall of the section are further provided with notches 48 combining in the assembled relation of the sections to form an opening for the passage of the arm 33 and other notches 15 49 combining to form an opening for the reception of the housing 12. The sections of the casing may be held in assembled relation by a securing element 50 directed through openings 51 formed in the side walls thereof. 20 It will be obvious that a construction of this character may be very readily and cheaply produced and will be durable and efficient in service. It will also be obvious that the construction hereinbefore set forth 25 is capable of a certain range of change and modification without departing from the spirit of the invention and we accordingly do not limit ourselves to such specific structure except as hereinafter claimed.

30 We claim:—

1. In a rotating electric fan structure, a fan motor, a casing therefor, a base, a neck connecting the base and motor casing, the neck being formed in two relatively rotatable sections one of which is secured to the motor casing and the other of which is secured to the base, a sleeve secured to the first named neck section and rotatably extended through the last named neck section, a thrust bearing 40 between the neck sections and surrounding said sleeve, a collar on the lower end of said sleeve confronting the lower end of the last named neck section, a thrust bearing interposed between said collar and the lower end

of the neck section, concentric conducting 45 tubes within said sleeve and insulated from one another and the sleeve, a connection strip supported from the base and contacts carried by said connection strips and engaging the ends of said tubes, the upper ends of said 59 tubes being connected to the motor leads.

2. In a rotating electric fan structure, a fan motor, a casing therefor, a base, a neck connecting the base and motor casing, the neck being formed in two relatively rotatable 55 sections one of which is secured to the motor casing and the other of which is secured to the base, means connecting the neck sections while permitting relative rotation thereof, a gear secured to the base section, a shaft 60 driven from the motor and having a gear, a counter-shaft supported from the first named neck section having pinions engaging said gears, a cover for said gearing formed in two sections having coacting notches combining 65 to produce apertures for the passage of the neck, means for holding the sections in assembled relation and means securing the sections of the guard to the first named neck section. 70

3. In combination with a rotating fan structure including a motor, a casing therefor, a base, a neck connecting the base and casing and permitting relative rotation thereof, means causing relative rotation when the 75 motor is operated, means for transmitting current to the motor comprising concentric tubes co-axial with the neck and held against rotation with relation to the motor casing, electrical connections between the upper 80 ends of said tubes and the motor leads, a connection strip within the base and spring contacts carried by said connection strip and engaging the lower ends of said tubes.

In testimony whereof we hereunto affix 85 our signatures.

RALPH R. TURNER.
